UNITED STATES PATENT OFFICE.

BENJAMIN W. TUCKER, OF SOUTH ORANGE, NEW JERSEY, ASSIGNOR TO CORONA TYPE-WRITER COMPANY, INC., OF GROTON, NEW YORK, A CORPORATION OF NEW YORK.

TYPE-WRITING MACHINE.

1,283,366.

Specification of Letters Patent. Patented Oct. 29, 1918.

Continuation of application Serial No. 820,244, filed February 21, 1914. This application filed March 13, 1916. Serial No. 83,845.

To all whom it may concern:

Be it known that I, BENJAMIN W. TUCKER, a citizen of the United States, and a resident of South Orange, county of Essex, and

5 State of New Jersey, have invented certain new and useful Improvements in Type-Writing Machines, of which the following is a full, clear, and exact description.

This invention relates more particularly 10 to a foldable front strike or other visible typewriting machine in which the keyboard and the platen carriage are adapted when not in use to be brought into compact relation, and is a continuation of my application 15 Serial No. 820,244, filed February 21, 1914, which has matured into Patent No. 1,222,497, dated April 10, 1917.

One of the main objects of the invention 20 is to provide simple and efficient means whereby the keyboard as an entirety may be moved away from its connection with the type-bars so as to break its coöperative relation therewith when the keyboard is moved from a normal operative position upwardly 25 and rearwardly to a more compact position, and which is of such a construction that when the keyboard is moved downwardly to a normal operative position the parts will again be placed in operative connection with 30 the type-bars to adapt the latter to be operated on the depression of any of the keys.

Another object of the invention is to provide a foldable typewriting machine in which a standard or universal keyboard is 35 employed adapting each type-bar to be operated by an individual key.

Other objects of the invention are to provide a typewriting machine in which the main section or frame part and keyboard 40 section or frame part of the main frame may be variously constructed and made of a skeleton form to adapt the frame parts or sections to be placed within a separate carrying case or in which the frame is substantially of the usual form but in sections or 45 parts which permit relative folding thereof to adapt the machine to be used independently of a carrying case or placed in a separate carrying case while being transported; to provide simple and efficient means whereby a substantially direct connection may be 50 made between the key-operated levers of the

keyboard and the type-bars; and to provide simple and efficient means whereby the key-operated levers may have a substantially 55 uniform touch.

With these and other objects in view, the invention will be hereinafter more particularly described with reference to the accompanying drawings, which form a part of 60 this application, and will then be pointed out in the claims at the end of the description.

In the drawings, Figure 1 is a fragmentary sectional plan of one form of machine 65 embodying the invention; and

Fig. 2 is a longitudinal section taken on the line II--II of Fig. 1, certain of the parts being broken away and others shown in a diagrammatic form. 70

The main frame 10 may be of any suitable form or construction to adapt the different parts of the typewriter mechanisms to be supported thereon. As shown it comprises a main member, part or section 11 and a 75 keyboard member, section or part 12. The main frame part 11 is shown of a more or less skeleton character and is intended to be placed into another frame or casing or form the frame casing itself as preferred. The 80 frame part 11 has a rear wall 13 and side walls 14 at the upper forward portion of which is pivoted the keyboard frame part 12. The part 12 has side walls 15 substantially triangular in form and said walls are 85 connected together at their forward edges by a transversely extending bar 16. The side walls 15 are pivoted by screws 16^a or otherwise to lugs or parts upon the side walls 14 of the main frame part 11 so that said keyboard frame part 12 may be moved upwardly and rearward to the position shown in dotted lines in Fig. 2 and thereby reduce the lengthwise dimension of the machine, it being understood that suitable means not 90 shown is provided to support the frame part 12 in both its normal and compact positions. 95

A keyboard 17 of a standard or universal character wherein the type-bars are operated by individual keys is mounted upon the keyboard frame part 12 so as to fold therewith. A plurality of supporting rods 18 extends transversely between the side walls of the frame part 12 and on each of said rods is

mounted a plurality of key-operated levers 19 forming a series of sets, groups or banks of such levers. There are three rods 18, though this number may vary according to 5 the number of keys employed as a part of the keyboard. These rods are arranged so that the inner rod is somewhat higher than the middle, and the latter rod is somewhat higher than the one forward thereof and 10 all of the rods are arranged so that a line will intersect the axis of said rods. Each key-operated lever 19 has a substantially horizontally arranged arm 20 on one end of which is a finger key 21, and said arm 20 is 15 arranged to have a substantial bearing surface on its fulcrum rod. Each of the key-operated levers has a downwardly extending arm 22, and said arm 22 with the arm 20 forms a substantially bell-crank shaped lever. 20 The arms 22 of each key-lever are connected to a spring 23 and each spring is held to a transversely extending rod 24 carried by the keyboard frame part 12. These springs tend normally to force the key-operated levers 25 against bars 25 extending transversely of the machine between the sides 15 of the frame part 12. The bars 25 form stops and, the upper bar 25 is adapted to engage the arm 20 while the two lower bars 25 are adapted 30 to engage the vertically arranged arms 22 of the key-operated levers.

Type-bars 26 are pivotally mounted at 27 in hangers or in a segment as preferred and said type-bars are adapted to have a plurality of type thereon as usual, the number of type varying according to whether a single or double case shift is employed. The type-bars at their outer ends are supported on cushions 28 held to a curved frame or 35 plate 29, or the said type-bars may be otherwise supported. A link 30 extends from each type-bar forwardly and downwardly therefrom. One set of links 30 is supported by the ends of arms 31, the second set of 40 links by the arms 32, and the third set of links by the arms 33. The arms 31 to 33 are supported upon transversely extending rods and each arm is normally forced forwardly and downwardly by a spring 34 the inner 45 end of which is held to a transversely extending rod 35. The arms 31 to 33 may be pivoted to the links 30 or otherwise held to support the same and tend normally through the springs 34 to force the links and type-bars to their normal position as shown in 50 the drawings. The links supported by the arms 30 are operated by the uppermost key-operated levers 19, the links supported by the arms 32 by the middle key-operated levers 19, and the links supported by the lowermost arms 33 are operated by the lowest key-operated levers 19, the 55 position and arrangement of the links and the relative lengths of the arms of the 60 key-operated levers being such that the force 65

required to move the links is substantially the same with each bank of keys. As each key-operated lever is moved by one of the keys 21 its coöperating link will force the type-bar with a push action upwardly and 70 rearward against a platen 36 as usual and as soon as the key is released one of the springs 34 will restore the link and type-bar to their normal position. In case the machine is to be folded to a compact condition 75 the keyboard frame part 12 is moved upwardly and rearward as shown in dotted lines in Fig. 2 which will break the connection between the key-operated levers 19 and the links to adapt the key-operated levers 80 with the keyboard and parts mounted on the frame part 12 to be moved away from the links and over the main frame part 11, thus making a contact break joint connection 85 between the key-operated levers and said links 30.

The carriage 37 may be of any desired construction and is adapted to travel transversely of the machine and is controlled by suitable escapement mechanism, not shown, 90 in the usual or in any preferred way. The carriage 37 supports the platen 36 and has the usual parts coöperating therewith as paper feeding means, line-spacing mechanism, ribbon mechanism and other features 95 usually employed in typewriting machines but which form no part of the present invention and for that reason it was thought unnecessary to illustrate the same in detail. One of the spools 38 of the ribbon mechanism and the rocking frame 39 which serves as means for operating the ribbon mechanism and the escapement dogs are shown. The rocking frame 39 has a transversely extending bar 40 for operating the ribbon 100 mechanism and the escapement dogs to permit the carriage to have its letter space movement as usual and this rocking frame has vertical arms which are engaged by a transversely extending rod 41. The rod 41 110 connects two bell-crank levers 42 located on opposite sides of the machine and these bell-crank levers are pivotally connected to a universal bar 43 by means of upright arms 44 in substantially the same manner as the 115 Corona typewriter. The universal bar 43 is engaged by rearwardly extending lugs 45 on the type-bars and also on the spacing means so that the universal bar will move the frame 39 back and forth to perform its various 120 functions at the operation of each key. The spacing means may be connected to operate the universal bar in substantially the same manner as the type-bars 26 are operated by the keys 21. The space levers 46 are connected by the finger bar 47 and said space-levers 46 may be mounted on one of the 125 transversely extending rods 18 and connected to operate a part as 48 through a suitable link or links as already described. 130

The space levers and also the shift levers, if more than one are used, not shown, are mounted with the key-operated levers upon the frame part 12 so as to fold therewith 5 and when folded the keyboard is in compact relation to the platen carriage.

It will thus be evident that simple and efficient means is provided whereby the keyboard may be folded relatively to the type-bars and the platen carriage to adapt the machine to be made compact; and that a simple and effective break joint connection is secured whereby a substantially direct connection may be made between the type-bars and the key-operated levers which will permit the keyboard to be folded from a normal operative position to an inoperative compact position.

Having thus described my invention, I 20 claim as new and desire to secure by Letters Patent:—

1. In a typewriting machine, the combination of a main frame comprising two parts hinged together to fold and unfold, a keyboard having key-operated levers mounted upon one frame part and arranged in groups, type-bars mounted upon another part, a platen carriage mounted on the same part as the type-bars, and links arranged in 25 groups and each group of type-bar operating links adapted to be operated by independent groups of key-operated levers and having a direct break joint connection therewith.

2. In a typewriting machine, the combination of a main frame comprising a plurality of relatively movable parts having a normal position and an abnormal compact position, a keyboard having key-operated levers 40 mounted upon one frame part, type bars mounted upon another frame part, and links connected at one end to the type bars and having a direct contact break-joint connection with the key-operated levers at their 45 opposite ends.

3. In a typewriting machine, the combination of a frame comprising parts hinged together to fold from a normal position to an abnormal compact position, a keyboard having key-operated levers mounted upon one frame part, type bars mounted upon another frame part, and links connected at one end with the type bars and having a direct contact break-joint connection with the key-operated levers at their opposite ends.

4. In a visible typewriting machine, the combination of a main frame comprising a plurality of relatively movable parts having a normal position and an abnormal compact position, a universal keyboard having key-operated levers mounted upon one frame part, type-bars mounted upon another frame part, a platen carriage mounted on the same frame part as the type-bars, and links having 65 a direct contact and break joint connec-

tion at one end with the key-operated levers and pivotally connected at their other ends to the type bars.

5. In a typewriting machine, the combination of a main frame part, type-bars mounted upon said main frame part, a platen carriage also mounted upon said frame part, links arranged in groups one link for each type-bar, arms pivotally held on said main frame part and supporting each link at the outer end thereof, springs tending normally to force the arms in one direction to restore the parts to their normal operative position, key-operated levers arranged in groups to correspond to the groups of links having 80 their lower ends adapted to engage the ends of said links, and a frame part hinged to said main frame part on which the key-operated levers are mounted and adapted to fold upwardly and rearward to move the key-operated levers away from the links and place them over and above the main frame part.

6. In a typewriting machine, the combination of a main frame part, type-bars mounted upon said main frame part, a platen carriage also mounted upon said frame part, links arranged in groups one link for each type-bar, arms pivotally held on said main part and supporting each link at the outer end thereof, springs tending normally to 95 force the arms in one direction to restore the parts to their normal operative position, key-operated levers arranged in groups to correspond to the groups of links having one of their ends adapted to engage the ends of 100 said links, and a keyboard frame part hinged to the main frame part on which the key-operated levers are mounted and adapted to fold upwardly and rearward to move the key-operated levers away from the links 105 and place them over and above the main frame part.

7. In a typewriting machine, the combination of a frame comprising two relatively movable parts, one of which is movable from a normal position to an abnormal compact position, type bars mounted on one frame part, a keyboard having key-operated levers mounted on the other frame part, and links having a direct contact break-joint connection with the key-operated levers and operatively connected with the type bars between the pivotal points of said type bars and the type.

8. In a visible typewriting machine, the combination of a main frame comprising two relatively movable parts one of which is movable from a normal position to an abnormal compact one, type-bars mounted on one frame part, a keyboard having key-operated levers mounted on the other frame part, and links pivotally held to the type-bars and having a direct contact and break joint connection with the key-operated levers.

9. In a typewriting machine, the combination of a main frame part, a platen carriage adapted to travel along said main frame part, type-bars mounted to move upwardly and rearward on said main frame part, a plurality of banks of key-operated levers having one arm of each lever extending downwardly, stops for limiting the movement of the key-operated levers in one direction, springs normally forcing the key-operated levers to their normal operative position, links having a contact engagement with the key-operated levers adapted to operate each type-bar as its co-operating key-operated lever is depressed, and a foldable frame part on which all of the key-operated levers are mounted to partake of the folding movement thereof.
10. In a typewriting machine, the combination of a main frame part, a platen carriage supported thereon, type bars pivotally mounted in the main frame part and movable upwardly and rearwardly, a keyboard frame part held to the main frame part and movable from a normal position to a more compact position, key-operated levers mounted on the keyboard frame part and foldable therewith, springs held to the keyboard frame part and engaging the key-operated levers for forcing said levers to their normal position, and links having a direct contact engagement only with the key-operated levers and having a direct positive connection with the type bars intermediate the pivotal points of the type bars and the type-
11. In a typewriting machine, the combination of a main frame part, a platen carriage adapted to travel along said main frame part, type-bars mounted on said main frame part, a plurality of key-operated levers forming a part of a universal keyboard, stops for limiting the movement of the key-operated levers in one direction, springs normally forcing the key-operated levers to their normal operative position, links having a contact engagement with the key-operated levers adapted to operate each type-bar as its co-operating key-operated lever is depressed, and a foldable frame part on which all of the key-operated levers are mounted.
12. In a typewriting machine, the combination of a frame comprising relatively movable parts having a normal operative position and an abnormal compact position, key-operated levers mounted on one frame part, type bars mounted upon another frame part, links having a direct contact break-joint engagement at one end with the key-operated levers and pivotally connected at their opposite ends with the type bars, and yieldable means for normally forcing said links in one direction and supporting the free ends of said links in position to be engaged by the key-operated levers when the frame parts are in normal position.
13. In a typewriting machine, the combination of a frame comprising relatively movable parts having a normal operative position and an abnormal compact position, key-operated levers mounted on one frame part, type bars pivotally mounted upon another frame part, links having a direct contact break-joint engagement at one end with the key-operated levers and pivotally connected at their opposite ends with the type-bars between the pivotal points of the type bars and the type, and yieldable means for normally forcing said links in one direction and supporting the free ends of said links in position to be engaged by the key-operated levers when the frame parts are in normal position.
14. In a typewriting machine, the combination of a main frame, upwardly and rearwardly movable type bars pivotally supported in the main frame, a keyboard support pivotally held to the main frame and movable upwardly and rearwardly from a normal position to a more compact position, bell-crank levers pivotally mounted on the keyboard support having substantially horizontally extending portions carrying keys and depending portions, links pivotally connected at one end with the type bars intermediate the ends of said type bars, and means for normally forcing said links in one direction and supporting the free ends thereof in position to be directly engaged by the depending portions of the bell-crank levers when the keyboard support is in normal position.
15. In a typewriting machine, the combination of a main frame, upwardly and rearwardly movable type bars pivotally supported in the main frame, a keyboard support pivotally held to the main frame and movable upwardly and rearwardly from a normal position to a more compact position, bell-crank levers pivotally mounted on the keyboard support having substantially horizontally extending portions carrying keys and depending portions, links pivotally connected at one end with the type bars intermediate the ends of said type bars, and means for supporting the opposite ends of said links in position to be engaged by the depending portions of said bell-crank levers when the keyboard support is in normal position.
16. In a typewriting machine, the combination of a main frame, type bars mounted therein, a keyboard support pivotally held to the main frame to fold and unfold, bell-crank key-operated levers mounted in groups on the keyboard support, the levers of the different groups being of relatively different lengths, links pivotally connected at one end to the type bars and adapted to be actuated by said key-operated levers when the keyboard support is in normal unfolded position.

tion, and means mounted in the main frame for supporting the opposite ends of said links.

17. In a typewriting machine, the combination of a main frame, type bars mounted therein, a keyboard support pivotally held to the main frame to fold and unfold, bell-crank key-operated levers mounted in groups on the keyboard support, the levers of the 10 different groups being of relatively different lengths, links pivotally connected at one end

to the type bars and adapted to be actuated by said key-operated levers when the keyboard support is in normal unfolded position, and yieldable means mounted in the 15 main frame for normally forcing said links in one direction and for supporting forwardly extending ends of the links.

This specification signed this ninth day of March, A. D. 1916.

BENJAMIN W. TUCKER.
